UNITED STATES PATENT OFFICE

JOHN J. DESMOND, OF HUBBARD WOODS, ILLINOIS, ASSIGNOR, BY MESNE ASSIGNMENTS, TO LINE MATERIAL COMPANY, OF SOUTH MILWAUKEE, WISCONSIN, A CORPORATION OF DELAWARE

SWITCH

Application filed March 11, 1929. Serial No. 346,092.

This invention relates to certain new and useful improvements in switches and refers more particularly to remote control air break switches.

- 5 Switches of this nature are usually mounted on overhead structures and are therefore very often subjected to severe weather conditions, and in the past great difficulty has been experienced in protecting
- 10 the contacts against sleet and ice to insure free operation and perfect contact at all times. Sleet hoods have been provided which have more or less protected the contacts while engaged, but adequate means for
- 15 protecting the movable switch elements or blades when in open position have not been devised.

Therefore, it is an object of this invention to provide protecting means for the blade 20 of the movable switch member which is engageable therewith when in full open position to protect the same against the elements.

Another object of this invention resides in the provision of a protecting hood for the 25 blade of the movable switch member which has means engaging the blade in a manner similar to the contact clips of the stationary contact to prevent oxidation of the contact surface of the blade, to at all times keep the same clean.

And a further object of this invention resides in the provision of a protecting hood for the blade of the movable switch member when in open position which has means for 35 engaging the contact surfaces of the blade to prevent oxidation thereof and which means are so mounted as to accommodate any misalignment of the blade.

With the above and other objects in view 40 which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physi-

cal embodiment of my invention constructed according to the best mode I have so far devised for the practical application of the principles thereof, and in which:

Figure 1 is an elevational view of a switch 55 of the character described embodying my invention;

Figure 2 is an enlarged detail view of the movable protecting hood with parts broken away and in section to illustrate structural 60 details, and

Figure 3 is a cross sectional view taken through Figure 2 on the plane of the line 3—3.

Referring now more particularly to the 65 accompanying drawings in which like numerals designate like parts throughout the several views, the numeral 5 represents the base or support of one unit of a disconnecting switch and which usually forms 70 part of the supporting structure, not shown. Two or three units are usually mounted side by side to be opened and closed simultaneously, but as the several units are identical in construction, only one has been 75 shown and the description will therefore be in the singular.

Insulator standards 6 and 7 extend upwardly from the base 5 to mount supporting insulators 8 and 9, respectively. The supporting insulator 9 carries at its upper end a stationary contact 10 which is of conventional design, having contact clips 11 and means for anchoring the adjacent end of a line conductor 12, which is electrically connected with the blades 11 in any suitable manner.

Engageable between the blades 11 of the stationary contact 10 is the blade 13 of a movable switch member 14 including a 90 blade support 15 fixed on an insulator 16 carried by a mounting member 17 which is secured to a square shaft 18. The square shaft 18 is rotatably mounted by suitable bearing members 19 and is adapted to be 95 oscillated by means of a handle 20 pivotally connected with the outer free end of a lever 21 fixed to the shaft so that actuation of the handle 20 moves the movable switch member 14 to open or closed position. 100

The switch blade 13 is electrically connected with a second line conductor 22 by means of a flexible conductor 23 one end of which is fixed to the blade, as at 24, and the 5 other end of which is impinged between an anchor member 25 and a clamp plate 26. The adjacent end of the line conductor 22 which is securely clamped to the member 25, as at 27, is electrically connected with the 10 adjacent end of the flexible conductor through a terminal member 28 directly engaged with the clamping plate 26. The member 25 is fixed to the insulator 8 and the flexible conductor 23 is held out of contact with the supporting structure when the 15 switch is in either of its positions by link members 29 and 30 pivotally connected, as at 31, and having their free ends respectively connected with the member 25, as at 20 32, and with a movable switch member carried part 15, as at 33. Each link member consists of a pair of flat strips maintained in spaced parallel relation by the 25 members 25 and 15 and by suitable spacers (not shown) located at the point of pivotal connection 31 and at points 34 and 35 in the links 29 and 30, respectively, the flexible conductor being positioned between the spaced strips of the links and passing over 30 the spacers (not shown) located at the points 34 and 35.

When the switch member 14 is in closed position and its blade 13 is received between the contact clips 11, it is protected against 35 oxidation, and is protected against sleet and the like by a protecting hood 36 carried by the contact member 10 and having its open side substantially closed by a pivotally mounted closure 37, which is freely movable 40 out of the path of the blade 13 as it is engaged or disengaged with the stationary contact. This thoroughly protects the contacts while in closed position and when the movable switch member is moved to its full 45 open position, as illustrated in dotted lines in Figure 1, the blade 13 is protected against the elements by a second protecting hood 38 which is mounted between the outer ends of a pair of link members 39 pivoted at a 50 medial point to the link members 30, at the point 35, and pivotally connected at their inner ends with a second pair of links 40, as at 41, the free ends of the links 40 being connected with the links 29, at the point 34. 55 The arrangement of the links 29, 30, 39 and 40 thus constitutes substantially a pantograph which is so arranged that when a switch member is moved to its full open position the protecting hood 38 is moved 60 into engagement with the blade 13.

The protecting hood 38 is preferably formed of bendable metal and its rectangular shaped sides 42 are connected across the top by a wall 43 and across the forward 65 side by a wall 44, the width of the hood

being substantially equal to the distance between the links 39 and the sides 42 being riveted thereto, as at 45. Mounted within the hood 38 is a pair of clip members 46 which have lugs 47 medially secured thereto to extend through aligned openings 48 in the side walls 42 of the hood member with expansive springs 49 mounted thereon and confined between the clip members and the walls of the hood. The springs 49 normally 70 maintain the clip members 46 in engagement with each other and thus prevent oxidation of their contact surfaces. Pivotal movement of the clip members about their studs 47 is prevented by a pin 50 which extends 75 through aligned apertures in the links 49, the side walls 42 of the hood and the inner portions of the clip members, being retained against longitudinal movement by cotter pins 51 or the like at each end of the pin. 80

As the movable switch member 14 is moved to its full open position, the movement of the arms 39 due to the pantograph action of the link members is such that the hood member 38 is raised considerably above 90 the blade until the last few degrees of the closing movement, during which it is rapidly moved downward towards the blade to engage the clip members 46 therewith. The forward or lower portions of the clip members 95 are preferably flared, as at 52, to guide the blade 13 therebetween and inasmuch as the members 46 are substantially floatingly mounted they are free to accommodate any misalignment of the blade 13 to insure a 100 firm contact therewith to prevent oxidation of the blade while the switch member is in its open position.

From the foregoing description taken in connection with the accompanying drawings, 105 it will be readily apparent to those skilled in the art to which an invention of this character appertains that I have provided novel means for protecting the movable switch blade of switches of the character 110 described against oxidation when in either contact making or open position and wherein the means for protecting the blade when in open position is mounted so that its open sides face downwardly during both positions. 115

What I claim as my invention is:

1. In a switch, a contact member, a switch member movable into and out of contact therewith, a stationary protecting hood covering the switch member and the contact when engaged, movable protecting means remote from the switch member when the same is engaged with the contact member and engageable with the switch member when the same is moved to its open position, and means mounting the protecting means in a manner accommodating any misalignment of the switch member. 120

2. In a switch, a stationary contact, a switch member movable to and from engagement with the stationary contact, a protecting hood, means mounting the protecting hood whereby it is positioned remote from the switch member when the same is engaged with the stationary contact and covers the switch member when it is moved to full open position, and means carried by said protecting hood and snugly engaging the switch member to prevent oxidation of the switch member. 5
3. In a switch, a stationary contact including a yieldable contact clip, a switch member movable to and from closed position and adapted to be engaged by said contact clip when in closed position whereby oxidation of the switch member is prevented while in closed position, a protecting hood, means mounting the protecting hood whereby it protects the movable switch member when the same is in open position, and means carried by the protecting hood having a firm engagement with the contact surface of said movable switch member whereby oxidation of the switch member is prevented while in open position. 10
4. In a switch, a stationary contact, a movable switch member having a blade adapted to be engaged and disengaged from said stationary contact, a protecting hood, yieldably separable clip members carried by the protecting hood, and means mounting the protecting hood whereby it is disposed over said movable switch blade when the movable switch member is in its open position, the yieldably separable clip members of the protecting hood firmly engaging the blade to prevent oxidation thereof. 15
5. In a switch, a stationary contact, a switch member movable to and from engagement with said stationary contact, a support, link members connecting the support and the movable switch member, and a protecting hood carried by said link members whereby the protecting hood is movable relative to and over the switch member when moved to full open position. 20
6. In a switch, a stationary contact, a switch member movable to and from closed position and engaging the stationary contact when in said closed position, a support, link members connecting the movable switch member with the support, a protecting hood carried by said link members whereby the open sides of the protecting hood face downwardly during both open and closed positions of the switch member and whereby the protecting hood moves relative to and over the movable switch member when the same is moved to full open position. 25
7. In a switch, a stationary contact, a switch member movable to and from closed position and engaging the stationary con-
- tact when in said closed position, a support, link members connecting the movable switch member with the support, a protecting hood carried by said link members whereby the open sides of the protecting hood face downwardly during both open and closed positions of the switch member and whereby the protecting hood moves relative to and over the movable switch member when the same is moved to full open position, and freely movable clip members carried by the protecting hood and engageable with the contact portion of the movable switch member to prevent oxidation thereof, said clip means being yieldably urged to engagement with said movable switch member portion. 30
8. In a switch, a stationary contact, a movable switch member having a blade adapted to be engaged and disengaged from the stationary contact, yieldably separable clip members, and means movably mounting the yieldably separable clip members whereby they move toward and are engaged with the switch blade as the movable switch member is moved to open position, the clip members firmly engaging the blade to prevent oxidation thereof. 35
9. In a switch, a stationary contact, a movable switch member having a blade adapted to be engaged and disengaged from the stationary contact, clip members, means normally yieldably maintaining the clip members in engagement with each other to keep their contact faces clean, and means movably mounting the clip members whereby they move toward and are engaged with the switch blade as the movable switch member is moved to open position, the switch blade coming to rest with the clean faces of the clip members firmly engaging its opposite sides to keep the switch blade clean while the movable switch member is in open position. 40
10. In a switch, a stationary contact, a switch member movable to and from engagement with said stationary contact, a support, link members connecting the support and the movable switch member, clip members, and means mounting the clip members from one of the link members whereby they are movable to engagement with the switch member when it is moved to full open position, to protect the switch member against oxidation. 45
11. In a switch, a stationary contact, a movable switch member having a blade adapted to be engaged and disengaged from the stationary contact, yieldably separable clip members, means movably mounting the yieldably separable clip members whereby they move toward and are engaged with the switch blade as the movable switch member is moved to open position to prevent oxidation of the blade, and means whereby 50

the yieldably separable clip members are free to adjust themselves to the switch blade to insure a perfect contact between the sides of the switch blade and the clip members.

¶ In testimony whereof I have hereunto affixed my signature.

JOHN J. DESMOND.
